CLAIM

The ornamental design for a beard trimmer, as shown.

DESCRIPTION

FIG. 1 is a perspective view of a beard trimmer showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines in the drawings illustrate portions of the beard trimmer that form no part of the claimed design.
